UNITED STATES PATENT OFFICE.

LOUIS RASCH, OF NEW YORK, N. Y., ASSIGNOR OF ONE-THIRD TO GEORGE W. DICKERMAN, OF NEW YORK, N. Y.

PILOT-LIGHT FOR GAS-BURNERS.

1,244,130.

Specification of Letters Patent. Patented Oct. 23, 1917.

Application filed January 2, 1917. Serial No. 140,172.

To all whom it may concern:

Be it known that I, LOUIS RASCH, a subject of the Emperor of Germany, residing in the borough of Manhattan, city, county, and 5 State of New York, have invented certain new and useful Improvements in Pilot-Lights for Gas-Burners, of which the following is a specification.

This invention relates to pilot lights; that 10 is to lights used with a bypass for lighting the main jet of gas burners, and especially to pilot lights in which a coned shield is employed in connection therewith.

A pilot light made in accordance with this 15 invention comprises a jet or burner surrounded by a truncated coned shield so disposed that the flame passes through the orifice at the apex, the cone being closed at the base and provided with holes near the base.

20 Figure 1 is a cross section of one form of shield made in accordance with this invention.

Fig. 2 is a plan.

Fig. 3 is a cross section showing a modified construction.

The shield *a* is a hollow truncated cone closed at the base with holes *b* disposed near the base of the shield to supply air to the small flame *d*. The pipe *c* carries the 30 gas to the flame and is shown passing through the center of the base of the cone or shield.

In the form shown in Fig. 3 the holes *b* point toward the base for the purpose of preventing the air flowing directly into the flame.

In use, when the pilot light is burning, the shield becomes hot and the air which supports combustion is warmed in passing 40 through the small holes near the base of the shield and by the surrounding cone, the air is directed into the flame, which issues from the truncated end of the conical shield. The flame preferably normally projects from the 45 smaller end of the shield and toward the apex of point of convergence, rendering the combustion of the gas complete and producing a long and pure flame. With a pilot light made in accordance with this invention, 50 the flame will not be extinguished even in a violent draft of air, or by explosion or suction.

This pilot light produces a long, strong

blue flame which issues from the small open end of the incasing portion of the device *a* 55 and is practically inextinguishable. The flame, however, is not truly a Bunsen flame since the air entering the air ports *b* mingles with the gas issuing from the pipe *c* at the point of combustion. In operation the air is 60 drawn into the incasing through the air holes by means of the heat produced. The holes in some instances are directed downwardly and have a tendency to give a downward direction to the air, which air upon becoming warm rushes with great force toward 65 and out through the open end and in so doing stretches out the small original flame until it issues through the mouth of the incasing, thereby converting the original weak 70 yellow flame into a long, strong, blue, practically inextinguishable one. It is to be noted that the gas outlet of the burner is located between the open top of the incasing *a* and the air openings in the sides of such 75 incasing. Of course, it is to be understood that the area of these air openings relatively to the chamber space within the incasing and the opening at the small end through which the flame passes, are to be properly 80 proportioned relatively to the amount and quality of gas intended to be used so that sufficient air will be supplied to maintain perfect combustion and the flame will be so proportioned to the opening through which 85 it passes that air will not find an entrance at that point.

What I claim is:—

In a pilot light for gas burners, the combination with a shield in the form of a truncated cone having an open top and a closed bottom disposed in the plane of the base of the cone, the sides of the shield being provided near the bottom with air openings directed toward the bottom, and a gas burner 90 within said shield having its gas outlet between the said open top and air openings and so located that the flame thereof may pass out through the said open top.

In witness whereof I have hereunto signed 100 my name in the presence of a subscribing witness.

LOUIS RASCH.
